UNITED STATES PATENT OFFICE.

RUDOLPH CONRADER, OF ERIE, PENNSYLVANIA.

PUMP.

1,178,217.

Specification of Letters Patent.

Patented Apr. 4, 1916.

Application filed March 30, 1914. Serial No. 328,144.

To all whom it may concern:

Be it known that I, RUDOLPH CONRADER, a citizen of the United States, residing at Erie, in the county of Erie and State of Pennsylvania, have invented new and useful Improvements in Pumps, of which the following is a specification.

This invention relates to pumps, and consists in certain improvements in the construction thereof as will be hereinafter fully described and pointed out in the claims.

The invention is illustrated in the accompanying drawings as follows:

Figure 1 shows a central vertical section of the pump. Fig. 2 a similar section of a portion of one of the sand traps. Fig. 3 a section on the line 3—3 in Fig. 1. Fig. 4 a section on the line 4—4 in Fig. 1. Fig. 5 a section on the line 5—5 in Fig. 1. Fig. 6 a section on the line 6—6 in Fig. 1. Fig. 7 a section on the line 7—7 in Fig. 1. Fig. 8 an elevation of the discharge tube of the pump, the same being partly in section.

1 marks the working barrel, 2 the standing valve and 3 the pump plunger. The pump plunger has a sleeve 4. This sleeve is provided with a shoulder 5 in its upper end and the upwardly extending cups 6, 8 and 10 and the spacing rings 7 and 9 are arranged 20 on the sleeve 4. A spacing ring 11 is arranged below the cup 10 and the reverse cup 12 is arranged below the ring 11. The cups are clamped in place on the sleeve 4 by the plunger bottom 13 which is screwed on to 30 the bottom of the sleeve 4. The lower cup 12 has the beveled edge 14, the bevel extending inwardly, that is to say, the sharp edge of the bevel is on the inside of the cup. This beveled edge 14 extends into an annular 40 groove 15 in the bottom 13. This annular groove makes such a fit with the bevel 14 that it does not prevent the outward movement of the wall of the cup 12 so as to form a joint with the working barrel but it does 50 prevent the spreading of the walls of the cup so as to come in contact with the tubing when the plunger is being inserted in the well.

It will be noted that the spacing ring 11 has concave surfaces so as to conform to the shape of the lowest upwardly extending cup and the reverse cup. It will also be observed that the plunger bottom 13 has an extension 13^a extending upwardly into the cup 12. The purpose of the shaping of the spacing ring 12 is to give proper support to the

opposite faced cups and the purpose of the extension 13^a is to so arrange the space that four cups will be firmly clamped by the bottom on the same length of tube or sleeve 4 so that would be used with four cups all facing upwardly. This is of importance in that it permits of the application of this feature of my invention to plunger sleeves already in use, the only new parts required for this feature being the spacing ring 11 and bottom 13 and the cup 12 with the inward bevel.

The plunger bottom has the inwardly extending lip 16 in which is arranged a perforation 17. A screw 18 extends through this perforation. It has a shoulder 19 which engages the lips 16 and prevents the withdrawal of the screw. A stem 20 extends upwardly from the bar 20^a in the bottom and the spring 21 is arranged between the bar 20^a and the head or shoulder 19 so that the screw 18 is forced downwardly with a yielding pressure. The screw is adapted to enter the screw threaded perforations 22 in the top of the standing valve 2 so that the standing valve may be pulled with the plunger.

The upper end of the plunger has a screw threaded portion 23 on which the crown 24 is secured. The seat 25 is secured by the crown as it is screwed to place. The ball valve 26 operates on the seat 25 and is carried by the crown. A tube 27 is screwed into the top of the crown. A sand trap 28 is formed around the tube 27 on the crown. The sand trap is provided with the clearing perforations 29. The bottom of the sand trap has the guide ways 30 forming slanting surfaces leading to the perforations. A collar 31 is screwed onto the tube 27. This collar is internally and externally screw threaded and the discharge tube 32 is screwed into the internal thread. This tube 32 has the jet openings 33 which are directed 100 into a sand trap 34. The upper end of the tube is provided with a ring 35 forming a loose fit with the tubing and the tube 32 has a sucker rod connection in the form of a cap 36.

In order to assure a filling of liquid back of the lower cup 12 should there be a sealing between the beveled edges 14 and 15 I provide passages 15^a leading through the bottom 13.

I do not claim in this application the form of sand trap shown nor the special

structure of the standing valve as these form the subject matter of separate applications filed on even date herewith #820,143, and #828,145.

5 What I claim as new is:—

1. In a pump, the combination of a barrel; and a plunger in the barrel comprising a series of cups, one of said cups being reversed and having its edge beveled inwardly.
- 10 2. In a pump, the combination of a barrel; a plunger in the barrel comprising a series of cups, one of said cups being reversed and having its edge beveled; and a ring overlapping the beveled edge and locking the cup against spreading.
- 15 3. In a pump, the combination of a barrel; a plunger in the barrel comprising a series of cups, one of said cups being reversed and having its edge beveled inwardly; and a plunger bottom adapted to clamp the cups, said plunger bottom having a ring overlapping the beveled edge of the reverse cup and locking the reverse cup against spreading.
- 20 4. In a pump, the combination of a barrel; a plunger in the barrel comprising a se-

ries of cups, one of said cups being reversed and having its edge beveled; a ring overlapping the beveled edge and locking the cup against spreading; and a passage leading through the ring for supplying liquid to 30 the inner surface of the reverse cup.

5. In a pump, the combination of a barrel; a plunger in the barrel comprising a series of cups, one of said cups being reversed and having its edge beveled inwardly; and a 35 plunger bottom adapted to clamp the cup, said plunger bottom having a ring overlapping the beveled edge of the reverse cup and locking the reverse cup against spreading, said ring having a passage through it for 40 supplying liquid to the inner surface of the reverse cup.

In testimony whereof I have hereunto set my hand in the presence of two subscribing witnesses.

RUDOLPH CONRADER.
